UNITED STATES PATENT OFFICE.

GEORGE W. HUGHS, OF FORT WORTH, TEXAS.

WIRE-STRETCHER.

SPECIFICATION forming part of Letters Patent No. 518,406, dated April 17, 1894.

Application filed September 30, 1893. Serial No. 486,885. (No model.)

To all whom it may concern:

Be it known that I, GEORGE W. HUGHS, a citizen of the United States, residing at Fort Worth, in the county of Tarrant and State of Texas, have invented a new and useful Wire-Stretcher, of which the following is a specification.

The invention relates to improvements in wire stretchers.

10 The object of the present invention is to improve the construction of wire stretchers, and to provide a simple and inexpensive one, which may be readily employed for taking up the slack of a fence wire at a point between fence posts.

15 A further object of the invention is to provide a device, which will be also capable of cutting wire, loosening and drawing staples and the like.

20 The invention consists in the construction and novel combination and arrangement of parts, hereinafter fully described, illustrated in the accompanying drawings, and pointed out in the claims hereto appended.

25 In the drawings—Figure 1 is a perspective view of a wire stretcher constructed in accordance with this invention. Fig. 2 is a longitudinal sectional view, the wire cutting recesses being arranged to receive the wire.

30 Like numerals of reference indicate corresponding parts in both figures of the drawings.

1 and 2 designate similar members of a wire stretcher pivoted together, and constituting a pair of tongs, and each consisting of a curved 35 jaw 3 and a shank 4. The curved jaws have V-shaped recesses or claws, and are oppositely beveled to enable the jaws to pass each other readily a short distance, in order firmly to grip a wire. The pivot 5, which secures

40 the members 1 and 2 together, also serves as the means for attaching a pivoted longitudinally disposed rack bar 6, which is provided at its inner end with an enlarged perforated head to receive the pivot 5. The rack-bar is

45 arranged midway between the jaws, and is provided with a series of outwardly shoudered teeth 7, any one of which is adapted to engage a fence wire, which should be arranged in the recesses or claws of the outer 50 ends of the jaws, when the latter are spread,

whereby when the jaws are closed upon said wire a loop will be formed, which may be readily twisted by turning the wire stretcher. The series of teeth enable loops of different sizes to be made to regulate the tension of the wire, and to avoid a great amount of twisting. One of the shanks is provided at its outer end with a hook, and the other is provided with a claw to enable staples to be readily loosened and removed.

60

The jaws are provided adjacent to the pivot with wire receiving recesses 8, adapted for the reception of a wire when they register and designed to be moved away from each other by turning the members 1 and 2 on the pivot 5 to cut a wire.

65 It will be seen that the device is simple and comparatively inexpensive in construction, and that it is capable of readily stretching a fence wire at an intermediate point between fence posts to the desired tension.

70 Changes in the form, proportion, and the minor details of construction may be resorted to without departing from the principle or sacrificing any of the advantages of this invention.

75 What I claim is—

1. A wire stretcher comprising a pair of pivoted members provided with oppositely disposed jaws, and a rack bar carried by the members and arranged between the jaws and provided with a series of teeth, substantially as described.

80 2. A wire stretcher comprising a pair of similar members each provided with a jaw and having a shank, a pivot connecting the members, and a longitudinally disposed rack bar provided at its inner end with an opening to receive said pivot and extending outward therefrom and arranged between the jaws and provided with a series of teeth, substantially as and for the purpose described.

85 3. In testimony that I claim the foregoing as my own I have hereto affixed my signature in the presence of two witnesses.

GEORGE W. HUGHS.
